United States Patent Office

Des. 199,189
Patented Sept. 22, 1964

199,189

DICTATING MACHINE

Roy M. Bloom, 13 Harcourt Road, Scarsdale, N.Y.

Filed Dec. 23, 1963, Ser. No. 77,912

Term of patent 14 years

(Cl. D26—14)

FIG. 1.

FIG. 4.

FIG. 2.FIG. 3.FIG. 5.FIGURE 1 is a front perspective view of a dictating machine showing my new design;

FIGURE 2 is a top plan view thereof on an enlarged scale;

FIGURE 3 is a front elevational view thereof;

FIGURE 4 is a side elevational view thereof; and

FIGURE 5 is a rear elevational view thereof.

The left side of the machine, not shown, is substantially plain and unornamented.

I claim:

The ornamental design for a dictating machine, as shown and described.
